[57] CLAIM

The ornamental design for a carton, as shown and described.

DESCRIPTION

FIG. 1 is a top perspective view of a carton showing my new design;

FIG. 2 is a top plan view;

FIG. 3 is a side elevation; and

FIG. 4 is a plan view of the carton in an unfolded condition.

The broken lines represent fold lines.

FIG. 1

FIG. 2

FIG. 3

FIG. 4
